CRANKCASE SCAVENGER

Clark C. Randall, Oak Park, Ill.

Application June 6, 1947, Serial No. 753,109

3 Claims. (Cl. 123—41.86)

1

This invention is directed to new and useful improvements in crankcase scavengers whereby the crankcase of an internal combustion automotive engine is thoroughly and efficiently ventilated of all undesirable fumes, gases and vapors produced during the operation of such engine.

The inventions disclosed herein are modifications, refinements and improvements on the crankcase scavenger described in my United States Letters Patent No. 2,406,103 dated August 20, 1946. While utilizing the same basic idea of creating the pressure necessary to produce the vacuum to exhaust the fumes from the crankcase by use of the flywheel teeth certain important changes in construction of the parts will be noted.

The primary object of this invention is to provide an efficient crankcase scavenger or ventilator that will produce the necessary combination of high volume of removal at low velocity.

Another object of this invention is to provide a crankcase scavenger whereby increased pressure is obtained from the flywheel teeth and directed to an improved aspirator or Venturi attachment whereby an increased volume of undesirable crankcase fumes are removed from the crankcase.

Still a further object of the invention is to provide such a device wherein there is provided adequate means for preventing the removal of desirable liquid lubricants from the crankcase during the operation of the scavenger.

A still further object is to provide in a crankcase scavenger an improved aspirator attachment.

Another object of the invention is to provide an improved, efficient airscrap for obtaining pressure from the flywheel teeth.

And yet another object of the invention is to provide in a scavenger of this type a baffle means for preventing liquid lubricants of the crankcase from being removed by the scavenger from the crankcase.

A further object of this invention is to provide in such a scavenger a novel separator or trap whereby any liquids that may have entered the scavenger from the crankcase will be separated from the undesirable fumes and be returned to the crankcase to continue their lubricating function.

Other objects and advantages will become apparent from an examination of the following detailed specification:

In the drawings:

Fig. 1 is a side elevational view of an internal

combustion automotive engine equipped with the improved crankcase scavenger embodying the inventions hereof.

Fig. 2 is a sectional view taken along line 2—2 of Fig. 1 showing the assembly of the airscrap with relation to the flywheel.

Fig. 3 is a perspective view of the improved airscrap attachment.

Fig. 4 is a vertical sectional view of the new aspirator or Venturi attachment.

Fig. 5 is an enlarged side elevational view of the separator and baffle assembly.

Fig. 6 is an enlarged side elevational view of the baffle attachment.

Fig. 7 is an enlarged end view of the baffle and separator assembly.

In detail, the engine block is indicated by reference character 1, the crankcase 2 and the flywheel casing 3. The usual air inlet to the crankcase is shown at 4 and an outlet from the crankcase is provided at 5.

Connected on the inside of the crankcase at outlet 5 is a baffle member 6 and connected to the outlet 5 outside of the crankcase is liquid and gas separator or trap 7. A conduit 8 leads from separator 7 to venturi or aspirator attachment 9. An airscrap 10 is secured to the flywheel casing 3 below and adjacent the flywheel 11, an appropriate opening having been cut in the bottom of the flywheel casing. A conduit 12 connects the airscrap 10 to venturi 9 to complete the general assembly of the scavenger.

In detail, the baffle assembly 6 comprises two spaced plates 13 and 14 secured together at their tops. The sides of the plates are spaced from each other to form vertical slots 15 and the lower edge of plate 13 is bent outwardly to form a lip 16. The outer plate 14 is of less height than the inner plate 13. Plate 14 has a central aperture 14' that aligns with the outlet 5 of the crankcase. Thus is formed a protected exit from the crankcase being in fact only a slot extending around the sides and bottoms of the two plates, the access to the bottom being further protected by lip 16 of inner plate 13. Bolts 17 are secured to the upper edges of the plates 13 and 14 and extend outwardly to form means for securing the baffle assembly to the inner side of the crankcase. The baffle thus formed is in fact a casing with a slot entrance at its bottom and an outlet in one side. A fitting 18 is positioned opposite the baffle on the outside of the crankcase wall 19 and is secured thereto, with a gasket 20 in between by means of bolt 21 and nut 22 and by means of nuts 23 tightened onto bolts 17.

Fig. 1 is a side elevational view of an internal

A conduit 24 is clamped to fitting 18 and leads to the bottom of separator 7. Separator assembly 7 comprises a tubular receiving chamber 25 horizontally disposed and provided with a removable cap 25'. The outlet from chamber 25 is a tube 26 that extends from a point outside and below the chamber 25 through the lower wall of chamber 25 to a point substantially above the floor of the chamber. Thus the separator 7 is provided with an inlet 27 at the bottom of receiving chamber 25 and an outlet 28 substantially above the bottom of chamber 25. The removable cap 25' is held in closed position by nut 29 threaded on bolt 30 that is secured to brace 31 that extends across the end of chamber 25.

The conduit 8 leads from the outlet tube 26 to the tube 32 of aspirator 9. Aspirator 9 has a crankcase or fumes inlet 33 and an aircoop or air pressure inlet 34 and one outlet passage 35. Tube 32 extends well below side inlet 34 as is usual in this type of aspirator. An outer tubular casing 36 forms the main body of the aspirator, surrounds tube 32 and extends well below its lower end. Within outlet passage 35 and spaced from its outer end and surrounding the outlet end of tube 32 is a restricting fitting 37 that has its inlet substantially the diameter of casing 36 and its lower outlet end 38 of less diameter than casing 36 but of greater diameter than tube 32. Thus the passageway from air inlet 34 to the outlet 35 is restricted adjacent the outlet of tube 32 but increases in area thereafter until outlet 35 is reached.

Airscoop 10 is provided with a cylindrical outlet 39 that merges into a small covered rectangular collecting chamber 40. The entrance to chamber 40 is an open flat bottomed channel or trough formed by bottom 41 and parallel sides or flanges 42 with upper edges diverging from the inner end of bottom 41 to the top of collecting chamber 40. Thus is formed an open channel 43 partially enclosing the teeth of the flywheel as they pass the aircoop for receiving the air from the flywheel teeth. Attaching extensions 44 provide means for securing the aircoop to the flywheel casing. Conduit 12 connects outlet 39 with inlet 34 of the aspirator.

The device is assembled on an engine by cutting a hole in the bottom of the flywheel casing adjacent the teeth of the flywheel and securing the aircoop as shown in Fig. 2. If no ventilating air inlet is provided in this casing then one is made preferably near or at the top. An outlet hole 5 is cut in the crankcase above the oil level and any other breather outlet located higher is plugged up. The baffle assembly is secured to this outlet as above described. The conduits connecting the baffle with the separator, the separator with the aspirator and the aircoop with the aspirator are then positioned and the assembly is ready for operation.

In operation the rotation of the flywheel teeth creates a blower action to drive air into the aircoop. It has been found that the flanged inlet channel 43 partially enclosing the flywheel teeth and the enclosed collecting chamber 40 located adjacent the point the teeth leave channel 43 results in highly efficient operation for the air moved by the flywheel teeth is thus collected and directed out of the aircoop with a minimum of loss. The baffle construction 6 makes it difficult for lubricating oil to be drawn or forced into the scavenger assembly and the separator 7 prevents oil that has entered the scavenger from being

discharged with the undesirable fumes, gases and vapors and permits its return to the crankcase. It is clear that the lighter gases and fumes will readily be drawn through the separator outlet 5 while the heavier oils will be held in the separator chamber and will return by gravity to the crankcase.

The novel aspirator 9 provides an additional restriction of the pressure from the aircoop seeking the outlet of the system, at a point adjacent the lower end of the inlet tube 32. The restriction is released within the aspirator, as shown and described, and this assembly has been found highly efficient in creating the desirable suction 15 to withdraw the undesirable vapors from the crankcase.

It is obvious that in some cases the scavenger may be advantageously installed directly to the outlet breather of the engine without cutting a new outlet in the crankcase casing and without using the baffle assembly. Also it may be desirable to omit the separator from the installation in certain instances where it is desired to minimize the cost of equipment or where the crankcase outlet is so positioned that there is little likelihood of oil entering the scavenger. However, the inclusion of both baffle and separator in the installation will assure efficient crankcase scavenging without loss of desired lubricating 30 oils.

I claim:

1. In a crankcase scavenger assembly for internal combustion engines wherein the teeth of the flywheel are utilized as the blower means, the improvement which comprises an aircoop having flanges at each side to provide a troughlike inlet wherein the teeth of the flywheel will be positioned to move air into the aircoop when in operation.

2. In a crankcase scavenger assembly for internal combustion engines wherein the teeth of the flywheel are utilized as the blower means, the improvement which comprises an aircoop having a collecting chamber and a troughlike inlet with parallel sides leading thereto and means for securing the aircoop adjacent the flywheel with a part of the teeth thereof extending within the troughlike inlet.

3. In a crankcase scavenger assembly for internal combustion engines wherein an aircoop is positioned on the flywheel casing to utilize the flywheel teeth as the blower means, the improvement which comprises an aircoop having a troughlike entrance formed by flanged sides extending upwardly from the bottom and means on the aircoop for securing it to the flywheel casing with said sides extending within the casing to position the teeth of the flywheel within the troughlike entrance.

CLARK C. RANDALL.
